UNITED STATES PATENT OFFICE.

JOSEPH E. GROAT, OF WEBSTER, MASSACHUSETTS, ASSIGNOR TO B. A. CORBIN AND SON COMPANY, A CORPORATION OF MASSACHUSETTS.

APPARATUS FOR TREATING SHOES.

1,269,429.

Specification of Letters Patent. Patented June 11, 1918.

Application filed March 9, 1917. Serial No. 153,786.

To all whom it may concern:

Be it known that I, JOSEPH E. GROAT, a subject of Great Britain, residing at Webster, in the county of Worcester and State 5 of Massachusetts, have invented certain Improvements in an Apparatus for Treating Shoes, of which the following description, in connection with the accompanying drawings, is a specification, like reference characters on the drawings indicating like parts in the several figures.

It has become a relatively common practice in recent years to subject the toe portion of a shoe to the action of steam or hot 15 vapor preparatory to lasting this part of the shoe, and sometimes also prior to pulling it over, for the purpose of softening the upper stock in this portion of the shoe and thus facilitating the lasting and pulling- 20 over operations. This practice was originally introduced to alleviate the difficulties experienced in lasting very high toed shoes and it was found so efficacious that the practice was very generally continued after the 25 high toed styles of lasts which originally brought it into use were discontinued. Another factor which has served to maintain the practice of steaming toes has been the wide use in the last few years of toe stiffeners of the "Vulco" and similar types. These 30 stiffeners are usually made from felt, or some similar material, impregnated with a composition that renders them very stiff and firm at ordinary temperatures but which 35 makes them very soft and pliable when heated somewhat above the usual temperatures. Before either pulling-over or lasting a shoe in which a toe stiffener of this type is used, it obviously is necessary to heat the stiffener 40 sufficiently to render it pliable. While it is not necessary to use steam or vapor merely for the purpose of softening the stiffener itself, it must be subjected to the action of a heated medium of some kind and usually 45 steam, or the hot vapor commonly termed steam, is employed for this purpose, both because it performs the function of softening the stiffener and also because it softens the other upper materials and thus facilitates 50 the lasting and pulling-over operations in a manner which could not be accomplished merely by the use of dry heat. The various forms of apparatus by which this heating and softening operation is accomplished are

known in the trade as "vamp steaming machines" "toe steamers", "toe softening machines" and the like.

Notwithstanding the fact that apparatus of this character is very generally used, a great deal of trouble is experienced due to 55 the damaging of the upper leather of the shoes while undergoing treatment in such apparatus. Sometimes the damage is caused by the spattering of hot water on the upper leather and sometimes by the fact that it is 60 subjected too long to the action of the steam used for this purpose or to the action of steam at too high a temperature. Even if the leather is not burned sufficiently to make it brittle and absolutely worthless, its finish 65 very frequently is damaged and the salability of the shoe thus is seriously impaired. Vegetable tanned leathers, which are largely used for upper stock, are particularly liable to be injured in the toe softening operation, 70 and it has therefore been proposed to make the toe caps of these shoes of chrome tanned leather, which is much less liable to be injured by excessive heat. The vamp and other portions of the upper may then be 75 made of any of the usual upper stocks, since there is no necessity for subjecting these parts of the shoe to the action of steam, and the liability of damaging the shoes in the softening operation thus is substantially reduced. It is found, however, that even 80 where this method is followed steam will often work back behind the toe cap to the vamp and either burn the vamp or spoil the 85 finish of the leather, as above described.

The present invention aims to eliminate the damaging of shoes which attends the practice of softening toes in the manner above described. To this end the invention provides a novel form of protecting device for the upper of the shoe which permits the softening of the stock at the toe by subjecting it to the action of a heated fluid medium in the usual way but protects the other parts of the shoe upper from the action of 90 this medium.

The invention will be readily understood from the following description, reference being made to the accompanying drawing, in which:

Figure 1 is an angular view of an apparatus embodying this invention;

Fig. 2 is a vertical cross sectional view of

the novel form of protecting device with which the apparatus shown in Fig. 1 is equipped; and

Fig. 3 is a rear elevation of the device shown in Fig. 2, showing the manner of engagement of this device with a shoe.

The invention is illustrated in the drawings as applied to a toe steaming apparatus, indicated in general at 2, of a form widely used by the trade. The invention may, however, be applied to any of the various toe steaming devices on the market, as for instance that shown in the Keyes Patent No. 1,094,548 granted April 28, 1914. The apparatus shown comprises a housing or casing of suitable shape supported on a hollow column which contains a body of water that is heated by means of steam. The steam or hot vapor rising from this body of water goes up through the casing and into the space into which the toe portions of the shoes are positioned. The apparatus illustrated is designed to steam two shoes at a time. Each shoe is supported in the apparatus by a protecting device of novel construction, both of said devices being secured to a support 4 which is fastened to the front of the steamer 2 by means of a bolt 5. The support 4 is provided with two substantially semi-circular notches 6 through which, respectively, the toe portions of the shoes project. This support preferably is made of some heat insulating material such as wood.

The protecting devices above referred to each comprises a flexible trough-like shield preferably made of sheet material of suitable character. This shield consists of a member 8 of canvas, duck, leather or the like bent into a U shape, as clearly shown in Fig. 1, and secured at its forward edge between the folds of another piece of sheet material 10, which preferably consists of an asbestos fabric. The fabric 10 is shown folded back upon itself, the edge of the part 8 is entered between the two parallel edge portions of the strip 10, and these two pieces are secured together by lines of stitches which form a hem in the forward edge portion of the part 10. A helical spring 12 is run through this hem and has its ends secured together above the shield. The shield is secured to the support 4 at substantially the middle portion of its forward edge so that the sides are left entirely free to assume any shape which may be given them by the spring 12 or by the shoe positioned in the protector. The securing means may conveniently consist of two L shaped clips 14 each having a horizontal arm riveted to the forward part 10 of the shield and a vertical arm screwed to a member 16 which is fastened to the front face of the support 4.

In using the apparatus, the workman places a shoe in the shield 8 and pushes it

forward until substantially all of the toe cap is projecting beyond the forward end of the shield. Normally the spring 12 holds the free side portions of the forward end of the shield drawn toward each other, as shown in Fig. 2, so that the space between said opposite sides is too narrow to receive a shoe for which the device is made. The act of inserting the shoe in the apparatus in the manner just described spreads the sides of the shield apart, as clearly indicated in Fig. 3, in which the shoe is shown in cross section, and the spring 12 acts on the side portions of the shield to draw them smoothly about the upper in the region of the rear edge of the toe cap and makes the shield conform substantially to the transverse contour of this part of the shoe. In other words, the shield adjusts itself automatically to the shape of this part of the shoe. The shield thus hugs the upper tightly enough to prevent any substantial amount of steam from working back along the upper into contact with the vamp where it might damage the upper leather in the manner above described. The toe portion of the shoe projecting in front of the shield, of course, is subjected to the action of the heated medium circulating in the casing 2.

The part 8 of the shield may be made of material which will be sufficiently stiff to support the weight of the shoe while still being flexible enough to perform the functions of a shield. While the forward part 10 of the shield may be made of any material suited to the requirements of the apparatus, it is found that an asbestos fabric is particularly adapted to this purpose because of its heat resisting properties.

While I have herein shown the best embodiment of the invention of which I am at present aware, it is obvious that this embodiment is susceptible of change and modification within the skill of the mechanic and the discretion of the designer without departing from the spirit or scope of the invention.

What is claimed as new is:

1. In an apparatus for subjecting the toe portion of a shoe to the action of a heated fluid medium, means for protecting the vamp of a shoe from the action of said medium constructed and arranged to conform automatically substantially to the contour of the upper of the shoe in the region of the rear part of the toe cap and presenting a continuous surface for engagement with the upper of the shoe.

2. In an apparatus of the character described, the combination with means for subjecting the toe portion of a shoe to the action of a heated fluid medium, of a protecting device arranged to embrace the shoe upper in the region of the rear portion of the toe cap and constructed to adjust itself

automatically substantially to the contour of said portion of the upper of a shoe positioned therein, said device being operative to leave the toe portion of the shoe exposed to 5 the action of said medium but to protect the upper of the shoe back of the toe portion from the action of said medium.

3. In an apparatus of the character described, the combination of a flexible shield 10 of sheet material shaped to fit over the vamp of a shoe leaving the toe portion of the shoe projecting therefrom, yielding means operative to draw the forward part of said shield snugly about the upper of the shoe in the 15 region of the rear edge of the toe cap, and means for directing a heated fluid medium against said projecting toe portion of the shoe.

4. In an apparatus of the character described, the combination of a flexible shield 20 of sheet material shaped to fit over the vamp of a shoe leaving the toe portion of the shoe projecting from the forward end of the shield, a spring acting on the forward part 25 of the shield to draw it snugly about the upper of the shoe in the region of the rear edge of the toe cap, and means for directing a heated fluid medium against said projecting toe portion of the shoe, the forward portion 30 of said shield being made of material adapted to protect the upper of the shoe from the action of said medium.

5. In an apparatus of the character described, the combination of a trough-like 35 shield of flexible sheet material, a support to which the middle portion of the forward end of said shield is secured leaving the side portions of the shield at said end free to move toward and from each other, and a 40 spring tending to pull said side portions toward each other.

6. In an apparatus of the character described, the combination of a trough-like 45 shield of flexible sheet material, a support to which the middle portion of the forward end of said shield is secured leaving the side

portions of the shield at said end free to move toward and from each other, and a helical spring extending along the forward edge of said shield and tending to pull said 50 free side portions toward each other.

7. In an apparatus of the character described, the combination of a trough-like shield of flexible sheet material, a support to which the middle portion of the forward 55 end of said shield is secured leaving the side portions of the shield at said end free to move toward and from each other, the forward part of said shield consisting of a strip of asbestos fabric, and a spring acting on 60 said free side portions to pull them yieldingly toward each other.

8. In an apparatus for subjecting the toe portion of a shoe to the action of a heated fluid medium, the combination of a flexible 65 shield shaped to fit over the vamp of the shoe leaving the toe portion of the shoe projecting therefrom, and means constructed and arranged to act on said shield to hold it snugly about the upper of the shoe in the 70 neighborhood of the rear part of the toe cap.

9. In an apparatus for subjecting the toe portion of a shoe to the action of a heated fluid medium, the combination of a flexible shield having a part consisting of textile 75 heat insulating material constructed to fit over the vamp of a shoe leaving the toe portion of the shoe projecting therefrom, and means acting yieldingly to hold the edge of said shield snugly about the upper of the 80 shoe in the neighborhood of the rear part of the toe cap.

10. The combination with a treating chamber having an aperture as described, of jaws movable relative to the edges of 85 the aperture and adapted to embrace an object in the aperture, and means for holding said jaws in operative position.

In testimony whereof I have signed my name to this specification.

JOSEPH E. GROAT.
